(57) **CLAIM**

The ornamental design for a computer input device, as shown and described.

DESCRIPTION

FIG. 1 is a rear view of a computer input device, showing my new design;

FIG. 2 is a front view thereof;

FIG. 3 is a left side view thereof;

FIG. 4 is a right side view thereof;

FIG. 5 is a perspective top view thereof;

FIG. 6 is a bottom view thereof;

FIG. 7 is a top view thereof; and,

FIG. 8 is another top view thereof, wherein the computer input device is shown at a 15-degree incline.

The environment in which the computer input device is used includes a computer and a computer cable (e.g., a universal serial bus cable), neither of which form a part of the invention.
